UNITED STATES PATENT OFFICE.

WALTER UMSTEAD, OF JERSEYTOWN, PENNSYLVANIA.

DITCHING-MACHINE.

SPECIFICATION forming part of Letters Patent No. 788,965, dated May 2, 1905.

Application filed August 30, 1904. Serial No. 222,694.

To all whom it may concern:

Be it known that I, WALTER UMSTEAD, a citizen of the United States, and a resident of Jerseytown, in the county of Columbia and State of Pennsylvania, have invented a new and Improved Ditching-Machine, of which the following is a full, clear, and exact description.

The purpose of the invention is to provide a simple, durable, economic, and effective machine for making ditches for the purpose of underdraining land with tile, slate, or the like and to provide a construction of ditching-machine wherein the ditching mechanism may be conveniently raised and lowered bodily and held in adjusted position, so that by successive operations the ditch can be gradually deepened until the required depth is reached without undue strain on the team, producing a clean-cut ditch with straight-cut walls ready to be filled.

Another purpose of the invention is to so construct the plow that it will have a forwardly and downwardly curved point and a straight smooth shank by which the loosened dirt is carried until said dirt reaches a combined switch and wing all automatically adjustable on the shank of the plow, which switch directs the ascending dirt to one side edge of the plow-shank at the top of the ditch, where the wing, which travels over the surface of the ground, sweeps the dirt away from the mouth of the ditch. The wing and switch accommodate themselves to the difference of depth in the ditch.

Another purpose of the invention is to provide knives or cutters which serve to cut the sod and trim and straighten the sides of the ditch and in connection with their supports constitute guides for the plow.

The invention consists in the novel construction and combination of the several parts, as will be hereinafter fully set forth, and pointed out in the claims.

Reference is to be had to the accompanying drawings, forming a part of this specification, in which similar characters of reference indicate corresponding parts in all the figures.

Figure 1 is a right-hand side elevation of the machine, the axle being in transverse section. Fig. 2 is a front elevation of the machine. Fig. 3 is a horizontal section taken practically on the line 3-3 of Fig. 2, and Fig. 4 is a detail sectional view of the means employed for raising and lowering the ditching mechanism.

A represents the beam, which is preferably in the form of an inverted channel-iron, and the tongue or pole 10 is secured to the forward right-hand end portion of said beam. The axle 11 is an arched axle and is secured in any approved manner upon the upper face of the beam A. Its terminals 12 are straight, and on said terminal portions supporting wheels 13 are mounted to turn. A seat 11^a is provided, supported by a suitable standard 11^b, the said standard being secured to the axle in longitudinal alinement with the tongue or pole 10, and it may be here remarked that the neck-yoke is preferably mounted to slide on the said tongue, so that the horses can advance as the ditching mechanism is carried downward in deepening the ditch.

At the rear portion of the beam A a shaft 14 is mounted to turn, and this shaft extends beyond the left-hand side of the said beam, a crank-arm 15 being secured to the extending portion of the said shaft. This crank-arm 15 where it is joined to the shaft is provided with a ratchet-wheel 16, engaged by a pawl 17, pivoted on the beam A. The rearwardly-extending yoke 18 is loosely mounted at its extremities on the said shaft 14 within the beam A, and a pinion 20 is secured to the shaft 14 between the members of the yoke. This yoke at its right-hand side is provided with a longitudinal slot 19, and at the slotted portion of the yoke a guide-bar 22 is located, extending above and below said yoke. This guide-bar is adjustably secured to the yoke by a suitable bolt or its equivalent passed through the said slot. Friction-wheels 23 are pivoted at the end portions of the guide-bar 22, which friction-wheels are in vertical alinement with the space between the members of the yoke 18. The shaft 14 and con-

nected parts form a portion of an elevating device for the ditching mechanism to be hereinafter described.

The ditching mechanism is constructed as follows: A horizontal head-bar 24 is provided which is L-shaped in cross-section and at its rear end is provided with a projection 25 at the left-hand edge, and a flange 26 is carried upward from this projection parallel with the vertical member of the said head-bar, as is shown in Fig. 3. An anchor-plate 27 is secured to the right-hand side of the head-bar 24 at the rear, and this anchor-plate extends downward some distance below the said head-bar. A standard 28, angular in cross-section, is secured by means of the member facing the left-hand side of the device to the said anchor-plate 27, and in the outer longitudinal edge of this standard 28 a slideway 29 is formed. The lower end 30 of this standard is more or less forwardly and downwardly curved, as is shown in Fig. 1. The standard 28 extends some distance up above the head-bar 24 and some distance down below the lower edge of the anchor-plate 27. The shank 31 of a plow B is attached to the said standard 28, and the point 32 of the plow is secured to the curved portion of said standard, as is shown in Fig. 1, and, as illustrated in Fig. 2, the point 32 of the plow is readily detachable and is independent of the shank, so that said point may be replaced if broken or sharpened, as may be needed. The shank 31 of the plow B is perfectly straight and smooth, the straight portion commencing just above the point 32. A horizontal guide-plate 33 is secured to the said standard 28 at its left-hand side, and said guide-plate 33 extends forward almost in alinement with the forward end of the head-bar 24. The forward portion of the guide-plate 33 is curved inwardly and in direction of the right-hand side of the machine until the forward end of the said guide-plate 33 is practically in alinement with the central longitudinal portion of the standard 28. This guide-plate 33 at its lower rear portion is provided with an inclined cutting edge 34, preferably beveled at both sides of the plate, which edge serves to trim and straighten the sides of the ditch. A second plate 35 is secured likewise to the left-hand side of the said standard 28 at a point below the left-hand guide-plate 33, against which the lower plate 35 abuts, and the forward vertical edge 36 of this lower plate 35 is a cutting edge, being beveled upon both sides of the plate, and connects with the cutting edge 34 of the plate 33. The cutting edge 36 is adapted to cut the sod when the work of digging the ditch is commenced. Hangers 37 extend downward from the right-hand side of the head-bar 24. These hangers are straight at their upper portions and are then curved downward and to the right,

the curvature of the rear hanger being more pronounced than that of the forward hanger, and the rear hanger is much longer than the forward hanger. These hangers are usually secured in position by means of a clamping-plate 38, as shown in Figs. 1 and 3, although other means may be employed. The lower ends of both of the hangers are vertical, and the lower end of the forward hanger is made to engage with the inner face of the left-hand guide-plate 33 at the forward end of said plate. A right-hand guide-plate 39 is employed, being the fellow of the left-hand guide-plate 33; but the right-hand guide-plate 39 commences at the rear edge of the rear hanger 37, being preferably flush with the outer face of said hanger. The right-hand guide-plate 39 is curved at its forward end in direction of the forward hanger, and the inwardly-curved portions of both of the guide-plates are usually secured to the lower end of said forward hanger by means of the same bolt. At the lower rear portion of the right-hand guide-plate 39 a beveled cutting edge 40 is formed, corresponding to the cutting edge 34 on the left-hand guide-plate 33, and a knife 41 is secured to the lower end of the rear hanger 37, the outer face of the knife being flush with the outer face of said right-hand guide-plate 39. The lower edge of this knife is preferably inclined downwardly and forwardly to a greater or lesser extent, and its forward vertical edge 42 is the cutting edge. This knife acts as a sod-cutter for the right-hand side of the ditch, the cutting edge 36 of the plate 35 acting in the same capacity at the left-hand side of the ditch. I desire it to be understood that the lower edges of the said guide-plates 33 and 39 may be sharpened from their inclined cutting edges to their forward ends. An upwardly-extending and rearwardly-curved bracket 43 is secured to the upper end of the standard 28, and a rod 44 is attached to or made integral with the upper end of said bracket 43, which rod 44 extends vertically downward nearly as far as the lower left-hand plate 35. A spring 45 is loosely coiled around this rod. The rod 44 at its lower end is loosely passed through an opening in a transverse bar 46, against which the lower end of the spring 45 has bearing, as is best shown in Fig. 3. This bar 46 is attached to a horizontal foot 47, extending from the left-hand side of a clearing-wing C. This clearing-wing C consists of a body portion 48, more or less rectangular and which stands at an acute angle to the right-hand side of the shank of the plow and the right-hand edge of the plow-standard, the inclination of said body 48 being rearward and in direction of the right-hand side of the machine. At the inner edge of this body 48 a tongue 49 is formed, as is shown in Fig. 3, the said tongue being adapted to

lide in the said groove 29. In this manner he wing C has guided movement in a vertical direction on the said standard and relative to the shank of the plow. In the further construction of the wing a hood 50 is employed, located at the top of the wing and preferably integral with the body 48 thereof. This hood is even more or less of a slight upward slope and extends beyond the outer or right-hand face of the said body of the wing. The said hood is inclined to the right and forwardly from the rear vertical edge of the wing to and beyond the right-hand edge thereof, the hood being more or less triangular in general formation, and a switch-plate 51 is made integral with this hood, said switch-plate being more or less concaved at its outer or right-hand face. The said switch-plate 51 extends diagonally downward across the shank of the plow in direction of its left-hand side. A guard-plate 52 is provided for said switch-plate 51, being located at its forward edge, and this guard-plate is inclined from its upper edge downwardly and in direction of the left-hand side of the machine, meeting the forward edge of the said switch-plate at its bottom portion. In fact, the guard-plate 52 is exceedingly narrow at its lower end and wide at its upper end. It will be observed that the wing and the connected switch are free to move up and down relative to the standard and the shank of the plow.

The ditching mechanism is pivotally suspended from the beam A, and this is accomplished by pivoting a link 53 to the vertical member of the head-bar 24 at the front and to the right-hand member of the beam A and also through the medium of a wider link 54 in the shape of a channel-iron, which is pivoted between the side members of the said beam at a point adjacent to the axle and is pivoted to the wider rear portion of the head-bar 24 by means of a suitable pivot-pin 55, as is shown in Fig. 3. The lower end of a rack-bar 56 is pivoted on the said pin 55, and this rack-bar is passed up through the yoke 18, the teeth of the rack-bar engaging with the teeth of the pinion 20 at the rear of the beam and the friction-rollers 23 engaging with the plain back surface of the said rack-bar, as is shown in Fig. 1.

When the machine is to be carried to or from the scene of operation, the crank 15 is turned so as to cause the rack-bar 56 to travel upward and bring the ditching mechanism up close beneath the beam A, as is shown in Fig. 1, whereupon the point of the plow will be above the surface of the ground. When the ditch is to be commenced, the crank 15 is turned so as to carry the rack-bar 56 downward a sufficient distance to cause the plow-point to enter the ground the desired depth or to such a depth as not to seriously embarrass the team drawing the ma-

chine. The pawl 17 is then made to engage with the ratchet-wheel 16, and the ditching mechanism is held in its adjusted position, and at such time the bottom portion of the wing will rest upon the surface of the ground. As the machine is drawn forward a shallow ditch will be made, and as the earth is thrown up by the plow it will travel up the plain surface of the plow-shank until it strikes the switch-plate 51 and will then be directed by said switch to the right-hand side edge of said plow-shank and will fall on the ground at the mouth of the ditch, and as the machine advances the wing C, having the inclination above described, will gather up this dirt and sweep it away from the mouth of the ditch, leaving that portion of the ditch clear. The ditch is then completed by means of successive trips of the machine, the ditching mechanism being lowered as far as desired and held in adjusted position at each trip, the operation being the same throughout. At the initial operation the cutters 36 and 42 cut the sod and will sever any roots that may extend across that portion of the field where the ditch is to be made, and the plates 33 and 39 guide the point of the plow, holding it in the center of the ditch, as is shown in Fig. 2, and the cutting edges of the said guide-plates 33 and 39 serve to trim and straighten the side portions of the ditch.

A draft device 57 is attached to the forward hanger 37 at a point between its upper and its lower ends. By thus hitching the draft device to the said standard above the forward ends of the guides the point of strain is brought near the point of work, enabling the machine to be built very light.

Having thus described my invention, I claim as new and desire to secure by Letters Patent—

1. In a ditching-machine, a beam, a ditching mechanism beneath the beam, links pivotally supporting said mechanism from said beam, a pinion carried by the beam, means for controlling the movement of the pinion, a pivoted guide operating in conjunction with the pinion, and a rack-bar pivotally connected with the ditching mechanism and passed through the said guide to an engagement with the said pinion.

2. In a ditching-machine, a wheel-supported beam, a ditching mechanism, links pivotally connecting the ditching mechanism with the beam, said links being capable of occupying a folded position or a vertical position beneath the beam, and means for adjusting the ditching mechanism, comprising a shaft carried by the beam, a crank-arm on said shaft, provided with a ratchet-section, a pawl for engagement with the ratchet-section, a yoke loosely mounted on the shaft, a pinion secured to the shaft between the members of the yoke, a rack-bar pivoted to a

portion of the ditching mechanism and passed through the yoke to an engagement with the said pinion, a guide-bar for the rack-bar, and rollers mounted on the guide-bar.

5. 3. A plow comprising a straight smooth shank and a forwardly and downwardly curved point, and a clearing-wing extending rearwardly and outwardly from the outer edge of the plow-shank and having guided movement to and from the plow-point.
4. In a ditching-machine, a plow comprising a straight smooth standard and a downwardly and forwardly curved point, a clearing-wing mounted to slide at one side of the shank, a switch-plate extending from said clearing-wing diagonally over the shank of the plow, and a hood connecting the said upper portion of the said wing with the said switch-plate.
10. 5. In a ditching-machine, a plow consisting of a straight shank having a smooth outer face and a downwardly and forwardly curved point, a standard to which the plow is attached, a clearing-wing extending rearwardly and outwardly from the outer edge of the plow-shank and having guided movement on the plow-standard, a switch-plate having its inner face concave, which switch-plate extends downward and diagonally across the front face of the plow-shank, a guard for the forward edge of the switch-plate, and an upwardly and outwardly inclined hood at the upper portion of said wing and connected with the said switch-plate, a foot extending inwardly from the bottom of said clearing-wing, a bracket attached to the said standard at its upper portion and provided with a downwardly-extending section, a bar attached to the said foot and mounted to slide on said downwardly-extending section of the bracket, and a spring carried by the said extension of the bracket, having bearing on the said bar, which spring is placed under tension as the combined clearing-wing and its hood and switch-plate are moved in an upward direction.

6. In a ditching-machine, a plow comprising a shank having a straight and smooth forward face and a forwardly and downwardly curved point, a spring-controlled combined clearing-wing, hood and switch-plate mounted to slide relatively to the longitudinal axis of the shank of the plow, the switch-plate extending diagonally across the front face of the plow and the wing at an acute angle rearwardly and outwardly from an edge of

the shank, a wheel-supported beam, a head bar carrying the said plow, links connecting said head-bar with the said beam, and means for raising and lowering said head-bar and holding it in adjusted position.

7. In a ditching-machine, a head-bar, a plow comprising a straight shank and a forwardly and downwardly curved point, the plow being carried by said head-bar, standards extending down from said head-bar guide-plates attached to the said standards which guide-plates are curved at their forward ends and brought substantially together opposite the central longitudinal portion of the shank, one of the said guide-plate extending farther rearward than the other the distance between the working surfaces of the guide-plates being substantially the same as the width of the shank of the plow, and sod cutters carried by the rear lower portion of the said guide-plates.

8. In a ditching-machine, a head-bar, a plow comprising a straight shank and a forwardly and downwardly curved point, the plow being carried by the said head-bar standards extending down from said head bar, guide-plates attached to the said standards, which guide-plates are curved at their forward ends and brought substantially together opposite the central longitudinal portion of the shank, one of the said guide-plate extending farther rearward than the other the distance between the working surfaces of the guide-plates being substantially the same as the width of the shank of the plow, sod cutters carried by the rear lower portion of the said guide-plates, the lower edges of the said guide-plates adjacent to the said sod cutters being inclined and sharpened, a spring-controlled combined clearing-wing switch-plate and hood mounted to slide relative to the shank of the plow, the wing extending rearwardly and outwardly from the shank, the switch-plate extending diagonally in a downward direction at the front face of the shank, a wheel-supported beam, link connecting the head-bar with the said beam and means for raising and lowering the head bar and parts carried thereby.

In testimony whereof I have signed my name to this specification in the presence of two subscribing witnesses.

WALTER UMSTEAD.
